PANEL POCKET

John Visser, Grand Rapids, Mich., assignor to
 Grand Rapids Metalcraft Corporation, Grand
 Rapids, Mich., a corporation of Michigan

Application July 14, 1933, Serial No. 680,409

REISSUED
 APR 30 1940

5 Claims. (Cl. 206—19.5)

The present invention relates to panel pockets and more particularly to swingably mounted containers disposed within panel or wall openings.

The main objects of the invention are to provide a novel type of ash receiver, vanity case, match box or the like adapted for mounting within openings on the instrument board or wall of a motor car; to provide such a device which is rattle-proof when assembled; to provide such a device which may be economically manufactured; to provide such a device which may be conveniently installed; and, to provide such a device which is attractive in appearance and utilitarian in use.

15 The device herein shown and described is an improvement over the device of the Roedding Patent No. 1,589,230, issued June 15, 1926, to my assignee.

An illustrative embodiment of the instant invention is shown in the accompanying drawing, wherein:

Figure 1 is a perspective view of the container mounted in an opening of a panel or wall;

Figure 2 is a sectional view thereof on lines 2—2 of Figures 1 and 5;

Figure 3 is a similar sectional view but showing the container swung to open position;

Figure 4 is a sectional view on line 4—4 of Figure 2, a portion of the rear wall of the container being broken away; and

Figure 5 is a sectional view on line 5—5 of Figure 2, a portion of the top of the container being broken away.

Referring to the drawing in which like parts are designated by the same numerals in the several views, a panel or wall 1 such as a sheet metal instrument panel of a motor car or a wall thereof is provided with an opening 2 therein and here shown as generally rectangular in form. This opening in the panel is formed by a portion blanked or cut therefrom and turned inwardly to form a laterally projecting tongue 3 which is provided with a rectangular slot 4 and a pair of oppositely disposed notches 20 on each side thereof. The two opposite sides of the opening and the upper edge thereof are here shown provided with inwardly projecting flanges 5, 6 and 7 likewise blanked from the panel.

50 A receptacle of sheet metal or the like, generally designated 8, for detachably retaining and embracing a metal container 9 is provided with a face plate 10, preferably ornamental in character and having a handle or button 11, side walls 12 and 13, each here shown as provided with a

spring tensioned finger 14 generally U-shape in form and preferably blanked or cut therefrom, a bottom 15 having depending spaced cam members 16, each provided with an arcuate slot 21, and a rear wall 17 which is provided with a depending finger 18 preferably blanked or cut therefrom and adapted for engagement within the slot 4 when the receptacle is inserted within the panel opening as hereinafter described. The receptacle may, if desired, be in the form of a container per se but is here shown as adapted for embracingly retaining the detachably insertable container 9.

The receptacle 8 is generally rectangular in form and of a size adapting it for insertion within the panel opening 2. The depending cams 16 are disposed within the notches 20 and contact the inner side of the panel 1 to form fulcrum points thereagainst to permit swinging of the receptacle from the position shown in Figure 2 to the position shown in Figure 3. The spring tensioned fingers 14 blanked from the side walls 12, 13 frictionally engage the side edges of the panel opening 2 to prevent rattling and the depending finger 18 within the slot 4 limits the outward swinging movement of the receptacle. The arcuate slots 21 in the depending cams 16 are so shaped that when the receptacle is swung outwardly the lower edge of its face plate 10 is held in spaced relation to the panel as shown in Figure 3 to prevent marring of the panel in its opening and closing movement.

The container 9 is, as heretofore suggested, preferably removable from the receptacle 8 as best indicated by dotted lines in Figure 3 and is provided with a hinged cover 19 which is adapted to swing open when the receptacle is swung outwardly and to swing closed by contact with the upper edge and flange 7 of the panel opening 2 when the receptacle is swung inwardly as shown in Figures 2 and 3.

It will thus be seen that a novel type of device of the character herein shown and described has been provided and that the device is economical to manufacture, may be conveniently installed, is rattle-proof when assembled, and is attractive in appearance and utilitarian in use.

While but one specific embodiment of this invention has been herein shown and described, it will be understood that numerous details of the construction shown may be altered or omitted without departing from the spirit of this invention as defined by the following claims.

I claim:

1. In a device of the class described, a panel

provided with an opening therein formed by a portion blanked therefrom and turned inwardly to form a laterally projecting tongue, said tongue having a slot therein, and a container disposed 5 within said opening having depending spaced cams forming fulcrum points contacting the inner side of the panel to permit swinging the container outwardly from said panel and a finger carried by said container engaging within said 10 slot for limiting the outward swinging movement of the container.

2. In a device of the class described, a panel provided with an opening therein formed by a portion blanked therefrom and turned inwardly 15 to form a laterally projecting tongue, said tongue having a slot therein, and a container frictionally disposed within said opening having depending spaced cams forming fulcrum points contacting the inner side of the panel to permit swinging of 20 the container outwardly from said panel and a finger carried by said container engaging within a said slot for limiting the outward swinging movement of the container.

3. In a container adapted for insertion within 25 an opening in a panel formed by a portion blanked therefrom and turned inwardly to form a tongue, the tongue having a slot therein, said container being disposed within said opening and having depending spaced cams forming fulcrum points 30 contacting the inner side of the panel to permit swinging the container outwardly from said panel with the lower edge of its face in spaced relation to the panel, and a finger carried by said container and engaging within said slot for limiting

the outward swinging movement of the container.

4. In a device of the class described, a panel provided with an opening therein formed by a portion blanked therefrom and turned inwardly to form a laterally projecting tongue, said tongue having a slot therein and a pair of oppositely disposed notches adjacent each side thereof, and a container within said opening having depending spaced cams disposed within said oppositely disposed notches and forming fulcrum points 5 contacting the inner side of the panel to permit swinging the container outwardly from said panel with the lower edge of its face in spaced relation to the panel, and a finger carried by said container engaging within said slot for limiting the 10 outward swinging movement of the container.

5. In a device of the class described, a panel provided with an opening therein formed by a portion blanked therefrom and turned inwardly 20 to form a laterally projecting tongue, said tongue having a slot therein and a pair of oppositely disposed notches adjacent each side thereof, and a container within said opening having depending spaced cams, each provided with an arcuate slot, 25 said cams being disposed within said oppositely disposed notches and forming fulcrum points contacting the inner side of the panel to permit swinging the container outwardly from said panel with the lower edge of its face in spaced relation to the panel, and a finger carried by said container engaging within said slot for limiting the 30 outward swinging movement of the container.

JOHN VISSER.
